UNITED STATES PATENT OFFICE.

ALBERT BAUMGARTEN, OF FREEPORT, ILLINOIS.

LEMON-SQUEEZER.

SPECIFICATION forming part of Letters Patent No. 654,598, dated July 31, 1900.

Application filed March 3, 1899. Serial No. 707,607. (No model.)

To all whom it may concern:

Be it known that I, ALBERT BAUMGARTEN, a citizen of the United States of America, residing at Freeport, in the county of Stephenson and State of Illinois, have invented certain new and useful Improvements in Lemon-Squeezers, of which the following is a specification.

My invention relates to certain improvements in lemon-squeezers, one object being to provide a compact, ornamental, and powerful squeezer adapted for attachment to the edge of a shelf or other support and to lie close up to and approximately parallel with said edge, so as to obviate any upwardly or laterally projecting portions which might give it an unsightly appearance or be a serious obstruction to the use of the shelf or the support for other purposes.

26 A further object is to make a squeezer quick and convenient of operation and effective in extracting the juice in the best shape and with the least effort.

To these ends the invention consists in certain devices of novel form and arrangement combined to coact advantageously and effectively to accomplish the desired result.

In the drawings, Figure 1 is a side elevation of the complete squeezer in its preferred form. Fig. 2 is a plan of the same. Fig. 3 is a longitudinal vertical section in line 3 3 of Fig. 2. Fig. 4 is a vertical section in line 4 4 of Fig. 3 looking in the direction of the arrow 4. Fig. 5 is a similar section in line 5 5 of Fig. 3 looking in the direction of the arrow 5, and Fig. 6 is a horizontal section of the cup looking downward upon the drain or strainer in the lower portion thereof.

Referring to the drawings, A is a yoke-shaped frame adapted for attachment to the edge of a shelf or counter by means of a downwardly-projecting flange a. (Shown clearly in Fig. 4, where it is seen secured to said counter by means of a screw α .) Said yoke is provided at one end with a hook a', bearing upon its point an inwardly-projecting lug a'', and a cup B is fitted within this hook and supported upon the same against vertical movement by means of ribs b b', which embrace the hook 45 between them. The forward edge of the cup

is adapted to lie behind the lug a'', and the cup can be inserted only by entering this edge behind the lug and rotating the remainder of the cup about this edge as a center, any direct withdrawal of the cup from the hook 55 in the line of the pressing operation being prevented by said lug. The lower portion of the cup is provided with a forwardly-extending lip b'', perforated at b''' to let the juice run through, and said lip is arranged at a 60 proper inclination to prevent the flow of the juice over the extreme end thereof. The other end of the yoke is provided with a bearing a'', in which is guided a screw-threaded member C, provided at its outer end with a handle c and at its inner end with a cone c'. The bearing a'' is provided with a pawl D, preferably operated by gravity and for that reason pivoted upon a horizontal pivot d, but also being provided with an extension d', by 70 pressure upon which the pawl may be disengaged. The thread upon the member C is beveled upon one side and abrupt upon the other in the manner of an ordinary ratchet-tooth, and the operating end of the pawl, as 75 well as the beveled side of the thread, is on the side toward the cone. This enables the handle and cone to be advanced directly into the cup or the lemon contained therein until power is needed, when the rotation of the 80 handle engages the thread with the pawl and completes the advance more slowly and with great power. The cone is provided with a spiral groove run in the opposite direction from the thread, by means of which said cone 85 is advanced, so that the rotation necessary to crowd the cone into the lemon works the inner soft portions of said lemon into the skin, preventing the same from oozing out with the juice and clogging the strainer. A de- 90 pending bracket O, adapted to support a glass, is secured to the counter by the same screw x which holds the yoke A, a channel or groove in the flange a being provided for the upper end of said bracket. It should be noticed that the inside of the cone is screw-threaded to fit the end of the screw C upon the advancing member. By this means the cone is easily removable for cleaning as well as the cup.

The broad features of my invention I be- 100

lieve are not limited to the specific construction described or to the exact form or arrangement of the various parts thereof.

I claim as new and desire to secure by Letters Patent—

In a lemon-squeezer, the combination of two members, one of which is threaded in the other and one of which is provided with a suitable cup and the other with an opposing cone, said cone having an external spiral groove or thread running in the direction op-

posite to the thread between the two members; substantially as described.

In witness whereof I have hereunto set my hand, at Freeport, in the county of Stephenson and State of Illinois, this 24th day of February, A. D. 1899.

ALBERT BAUMGARTEN.

Witnesses:

LOUIS STROHACKER,
ED. STROHACKER.
